DISPLAY FIXTURE

Filed Aug. 2, 1948

FIG. 2

FIG. 1

INVENTOR.

Donald L. Mapson

UNITED STATES PATENT OFFICE

159,997

DISPLAY FIXTURE

Donald L. Mapson, Los Angeles, Calif.

Application August 2, 1948, Serial No. 147,891

Term of patent 14 years

(Cl. D80—9)

To all whom it may concern:

Be it known that I, Donald L. Mapson, a citizen of the United States, residing at Los Angeles, in the county of Los Angeles and State of California, have invented a new, original, and ornamental Design for Display Fixture, of which the following is a specification, reference being had to the accompanying drawing, forming part thereof.

Fig. 1 is a front elevational view of a display fixture showing my new design.

Fig. 2 is a side elevational view thereof.

I claim:

The ornamental design for a display fixture, as shown.

DONALD L. MAPSON.
